UNITED STATES PATENT OFFICE.

DAVID KISCH, OF NEW YORK, N. Y.

DESIGN FOR A PLAITING-BLADE.

SPECIFICATION forming part of Design No. 34,228, dated March 12, 1901.

Application filed January 12, 1901. Serial No. 43,080. Term of patent 7 years.

To all whom it may concern:

Be it known that I, DAVID KISCH, a citizen of the United States, residing in the city of New York, borough of Manhattan, in the county and State of New York, have invented and produced a new and original Design for a Plaiting-Blade, of which the following is a specification, reference being had to the accompanying drawings, forming part thereof.

Figure 1 is a plan view of a plaiting-blade embodying my design. Fig. 2 is a cross-section of the same on the line 2 2 of Fig. 1, and Fig. 3 is a cross-section of the same on the line 3 3 of Fig. 1.

The design comprises the blade *a*, presenting at its working edge the appearance of a number of transversely-disposed parallel tongues *b*, spaced apart from each other, such tongues joining the body of the blade by an

unbroken plane surface and the points of said tongues being beveled on one face and rounded convexedly and merged into the side edges of the tongues, as indicated at *b'*, whereby the blade is given an undulated or sinuous configuration.

Having thus described my invention, what I claim as new, and desire to secure by Letters Patent, is—

The design for a plaiting-blade, herein shown and described.

In testimony whereof I have signed my name to this specification in the presence of two subscribing witnesses.

DAVID KISCH.
